CONTROL FOR TANDEM ROTORED HELICOPTERS

Elliot Daland, Wallingford, and Donald N. Meyers, Philadelphia, Pa., assignors, by mesne assignments, to Piasecki Helicopter Corporation, Morton, Pa., a corporation of Pennsylvania

Application January 2, 1948, Serial No. 216

3 Claims. (Cl. 170—135.24)

1

This invention relates to rotary wing aircraft and more particularly to methods of rigging helicopters having equivalent lift rotors mounted in tandem. The term "equivalent lift rotors" is used herein to define rotors of substantially the same diameter and having substantially the same aerodynamic characteristics and operated at substantially the same rotative speeds.

In helicopters of this type it is now common practice to employ control systems wherein longitudinal control is obtained by differentially changing the collective pitch of the front and rear rotors. To tilt the machine downwardly the pilot decreases the collective pitch of the front rotor and increases the collective pitch of the rear rotor simultaneously, by moving the control column, provided for this purpose, forwardly. To tilt the machine upward, the control column is moved rearwardly by the pilot, simultaneously increasing the collective pitch of the front rotor and decreasing the collective pitch of the rear rotor.

Directional control is obtained by oppositely tilting the fore and aft rotors sideways by the use of cyclic pitch. Rudder pedals are provided for pilot operation to differentially apply cyclic control to the rotors to turn the machine to the right or left.

The rotors on this type of machine are turned in opposite directions to neutralize the torque reaction acting on the craft. We have found from actual practice that turning the rotors in opposite directions does not entirely neutralize torque reaction forces and a rudder correction must be made to maintain a straight course. This results in a partial loss of rudder control in the direction that the rudder correction is being applied. We have also learned from practice that when helicopters of this type are in forward flight attitude and the rotor blades of both rotors are set at the same incidence angle as has been common practice, the control column must be carried in a position ahead of mid-position to simultaneously increase the collective pitch of the rear rotor and decrease the collective pitch of the front rotor in order to equalize the lift of the two rotors. This limits the amount of forward control available and requires the use of additional total collective pitch.

The rotor blades of helicopters provided with the aforescribed control systems have been rigged in such a manner that the blades of both of the rotors are set at the same incidence angle when the control is in mid-position; and the directional control system has been rigged so that when the swash plates are horizontal, the rudder pedals are in a neutral position.

Accordingly, it is among the principal objects of the present invention to provide a method of rigging the rotor blades in the control system to

2

eliminate the climbing moment acting on the helicopter when in forward flight attitude and offset the turning forces necessitating the use of the rudder control.

Another object of this invention is the equalization of the degree of control that may be exercised by the use of the rudder pedals or other directional means provided.

Another object of this invention is to equalize the thrust of the two rotors by setting the blades of the rear rotor at a higher incidence angle than those of the front rotor when the control column is in a mid-position.

A further object of this invention is to provide a greater degree of control about the yawing and pitching axes of the aircraft.

The method of rigging as provided by our invention overcomes the faults and disadvantages attributable to former methods of rigging and obtains the objects and advantages outlined above.

While this invention may be applied to all helicopters of the tandem type, we have chosen for purposes of illustration, to show its application to the control system disclosed and described in the copending application by Elliot Daland Serial No. 729,565, filed February 19, 1947, the drawings of which are reproduced herein with slight modification to better illustrate this invention.

In the drawings, Figure 1 is an isometric view of the forward portion of the controls and a partial view of the front rotor.

Figure 2 is an isometric view of the aft portion of the controls and a partial view of the rear rotor.

A full description of all the details shown in the drawings will not be given here as they are described in the afore-mentioned pending application.

Referring more particularly to the drawings, the control system is comprised of a longitudinal and lateral control column 11, a total collective pitch control 12, and directional control pedals 13 and 14. These pilot actuated controls are mechanically connected to the swash plates 15 and 16 which act to change the pitch of the rotor blades 17 and 18. It is understood of course that two or more blades of the type shown are usually employed in each rotor.

Forward movement of the control 11 will simultaneously increase the pitch of the rear rotor blades 18 and decrease the pitch of the front rotor blades 17. Moving the control column 11 to the right will tilt the swash plates 15 and 16 to the right, cyclically changing the pitch of both rotors to bank the ship to the right. To bank the ship to the left the control 11 is moved to the left. Backward movement of the control column 11 increases the collective pitch of the front rotor and decreases the collective pitch of the rear rotor. Pushing the right rudder pedal 13 tilts

the front swash plate 15 and lift vector of the forward rotor to the right and tilts the aft swash plate 16 and rear rotor lift vector to the left turning the machine to the right. Pushing the left rudder pedal 14 causes an opposite effect. Upward movement of the control 12 increases the pitch of both rotors collectively. Downward movement of the control 12 decreases the pitch of both rotors collectively.

Our improved method of rigging consists of setting the front rotor blades 17 at a predetermined incidence angle when the longitudinal and total collective pitch controls 11 and 12 are in their mid-positions.

As the rear motor is acting in the downwash of the front rotor when the helicopter is in forward flight attitude or hovering into a wind, the angle of attack of the rear rotor blades 18 will be less than that of the front rotor blades 17 resulting in unequal lift distribution between the two rotors. To overcome this condition we set the blades 18 of the rear rotor at a higher incidence angle than those of the front rotor. This is done with the longitudinal and total collective pitch controls set in their mid-position.

The term incidence angle as used herein defines the relative angle between the chord line of the blade and the plane of rotation of the rotor. This adjustment is made without disturbing the vertical settings of the swash plates 15 and 16 by rotating the blades about their pitch axes. By doing this the thrust of the two rotors is equalized when the craft is flying at approximately its cruising speed with the total collective pitch and longitudinal control columns in their mid-positions.

It is now apparent from the foregoing description that this method of rigging provides the greatest degree of control each side of the mid-positions of the control members thereby eliminating the danger of running out of control as has happened with other systems of control rigging.

Because of the aforementioned downwash effect on the rear rotor and the geometry of the lift forces about the center of gravity of the machine, we have found that the rear rotor requires more power than that of the front rotor which results in a turning moment being set up about the yawing axis of the craft caused by the unequal torque reaction forces acting on the craft. To offset this turning moment we have rigged the directional control system in such a manner that when the rudder pedals 13 and 14 are in a neutral position the two swash plates 15 and 16 are tilted in the opposite directions as shown to apply directional cyclic control of the rotors to overcome this turning moment. This setting is obtained by adjusting the turnbuckles 19 and 20 in such a manner that the left rudder push-pull tube is lengthened and the right rudder push-pull tube is shortened.

Rigging the directional control in this manner eliminates the use of the rudder correction when the controls of the aircraft are in a cruising position and gains the advantage of allowing a full amount of rudder travel for control purposes.

We claim:

1. A helicopter control system comprising two equivalent lift rotors mounted in tandem, each of said rotors having one or more blades and being provided with blade pitch changing means, pilot actuated means for controlling the attitude of the helicopter about its pitching axis, means

70 connecting the pilot actuated means to said blade pitch changing means to simultaneously increase the pitch of the blades of one rotor and decrease the pitch of blades of the other rotor on imparting one kind of movement to the pilot actuated means, said connecting means and rotor blades being so adjusted that the angle of incidence of the rear rotor blades is greater than the angle of incidence of the forward rotor blades when the pilot actuated means is at the center of travel of said one kind of movement.

2. A helicopter control system comprising two equivalent, counter-rotating lift rotors mounted in tandem, each of said rotors having one or more blades and being provided with blade pitch changing means, pilot actuated means movable between two limiting positions for controlling the helicopter about its yaw axis, means connecting the pilot actuating means to said blade pitch changing means to oppositely tilt the thrust vectors of said rotors laterally on movement of said pilot actuated means, said connecting means and blade pitch changing means being so adjusted that the lift vectors of the rotors are oppositely tilted in a lateral direction when the pilot actuated means is centered with respect to said limiting positions.

3. A helicopter control system comprising two equivalent lift rotors mounted in tandem, blade pitch changing means located adjacent to each of said rotors, the blades of said rotors being connected to said blade pitch changing means for pitch adjustment, a first pilot control means, means connecting said pilot control means to said blade pitch changing means to simultaneously increase the pitch of one rotor and decrease the pitch of the other rotor, on imparting one kind of movement to said pilot control means, a second pilot control means movable between two limiting positions, and means connecting said second control means and said blade pitch changing means to oppositely tilt the thrust vectors of said rotors laterally upon actuation of said second control means by the pilot, the connecting means between the first-mentioned pilot control means and said blade pitch changing means being so proportioned and adjusted that the blades of the rear rotor are at a higher incidence angle than those of the front rotor when the first-mentioned pilot control means is at the center of travel of said one kind of movement, the connecting means between the second pilot control means and the blade pitch changing means being so proportioned and adjusted that the rotor thrust vectors are oppositely tilted laterally when the second-mentioned control means is centered with respect to said limiting positions, whereby to counteract the unbalanced torque of the rotors.

ELLIOT DALAND.
